UNITED STATES PATENT OFFICE.

OLAF SIGVART LUND, OF BANCROFT, IOWA.

SELF-LOCKING SPIKE AND TIE-PLATE.

1,129,498.

Specification of Letters Patent. Patented Feb. 23, 1915.

Application filed March 18, 1914. Serial No. 825,610.

To all whom it may concern:

Be it known that I, OLAF SIGVART LUND, a citizen of Norway, residing at Bancroft, in the county of Kossuth, State of Iowa, 5 have invented certain new and useful Improvements in Self-Locking Spikes and Tie-Plates; and I do hereby declare the following to be a full, clear, and exact description of the invention, such as will enable 10 others skilled in the art to which it appertains to make and use the same.

This invention relates to railroad tracks and has special reference to a spike and tie plate for use in connection with such tracks.

15 One object of the invention is to provide an improved form of spike which, when used with a tie plate, will lock against accidental withdrawal or loosening.

A second object of the invention is to 20 provide an improved form of tie plate so arranged as to slightly tip the rails inward toward the center of the track when placed on a horizontal tie surface.

With the above and other objects in view 25 the invention consists in general of certain novel details of construction and combination of parts hereinafter fully described, illustrated in the accompanying drawings, and specifically claimed.

30 In the accompanying drawings like characters of reference indicate like parts in the several views, and Figure 1 is a transverse section through a rail and the improved tie plate, the spikes being shown in position. 35 Fig. 2 is a bottom plan view of the tie plate.

In carrying out the objects of this invention there is provided a tie plate having a flat bottom surface 10 and disposed centrally of this bottom surface is a rib 11 40 which is triangular in cross section, both sides of the rib being inclined at the same angle with respect to the adjacent portions of the tie plate. Spaced from the rib 11 are other ribs 12 and the outer side of each 45 of these ribs 12 is vertically disposed with respect to the tie plate under surface and the inner sides of the ribs 12 are inclined similar to the inclined side of the rib 11.

This tie plate is provided with four 50 rectangular spike holes or openings 13 and thus

four spikes can be used if desired or two can be driven, either opposite each other, or in diagonal disposition. The upper surface of the tie plate is inclined downward toward the inner side so that the inner edge 55 of the tie plate is somewhat thinner than the part against which the outer edge of the rail base rests. A rib 14 is formed along this thickened part and against this rib butts the edge of the base of the rail 15. 60 The plate thus can be placed upon an ordinary tie and the ribs 11 and 12 engaged in the material of the tie and by reason of the perpendicular sides of the ribs 12 any side slipping of said plate will be prevented. 65 Furthermore by reason of the tapered transverse structure of the tie plate the head of the rail will be tilted slightly inward so as to prevent over-turning of the rail due to side swing of the engine or cars. In connection with this tie plate there is provided a spike 15' which is of the ordinary 70 shape with the section that is adjacent the head cut away as at 16 to provide a shoulder 17. Moreover the back of this spike is 75 provided with a curved portion 18. When a spike such as this is driven in the tie through the tie plate opening 13 it passes down through said opening in the usual manner but when the curved portion 18 80 contacts with the outer part of the opening or outer wall thereof the upper end of the spike is forced inward until the shoulder 17 engages the tie plate and locks the spike from accidental movement. The spike, however, can be removed by first lifting the 85 same slightly and then bending it forward so that the shoulder 17 is disengaged from beneath the tie plate.

There has thus been provided a tie plate 90 which will give the rails the proper inward inclination without making it necessary to cut a part of the wood of the tie and at the same time which will prevent slipping laterally of the rail. There has also been provided a spike which will automatically lock 95 from accidental withdrawal.

Having thus described the invention, what is claimed as new, is:—

A tie plate provided with ribs arranged 100

to extend transversely of the tie, said ribs comprising a center rib having both sides inclined to the bottom surface of the plate and two lateral ribs each having its outer 5 side perpendicular to the bottom of the plate and its inner side inclined with respect thereto.

In testimony whereof, I affix my signature, in the presence of two witnesses.

OLAF SIGVART LUND.
